J. R. BURKHARDT,
GRAVE VAULT,
APPLICATION FILED AUG. 11, 1921.

1,417,137.

Patented May 23, 1922.

Fig. 1.

UNITED STATES PATENT OFFICE.

JACOB R. BURKHARDT, OF SPRINGFIELD, OHIO, ASSIGNOR TO THE SPRINGFIELD METALLIC CASKET COMPANY, OF SPRINGFIELD, OHIO, A CORPORATION OF OHIO.

GRAVE VAULT.

1,417,137.

Specification of Letters Patent. Patented May 23, 1923.

Application filed August 11, 1921. Serial No. 491,380.

To all whom it may concern:

Be it known that I, JACOB R. BURKHARDT, a citizen of the United States, residing at Springfield, in the county of Clark and 5 State of Ohio, have invented certain new and useful Improvements in Grave Vaults, of which the following is a specification.

My invention relates to improvements in metallic grave vaults of the type known as 10 water tight vaults and it particularly relates to devices for guiding and latching the parts of the vaults together.

The type of vault to which the invention relates is one which employs a separate bottom and an air tight upper portion which constitutes the top, sides and ends. The object of this invention is to provide improved 15 latching devices for securing the parts of the vault together and to associate there- 20 with guides of a nature which will steer the upper portion of the vault to cause it to properly seat itself on the bottom to be latched by the catches.

In the accompanying drawings:—

25 Figure 1 is a vertical section through the vault showing my improved guides and locking devices applied thereto, the section being taken near one end thereof.

Fig. 2 is an enlarged sectional view on 30 the line 2—2 of Fig. 1 with the upper section of the vault removed.

Fig. 3 is a view of the inside of one of the housings which supports a catch and forms one of the guides.

35 Fig. 4 is an enlarged section on the line 4—4 of Fig. 1.

Fig. 5 is an enlarged section on the line 5—5 of Fig. 3.

Referring to the drawings, the upper portion 40 of the vault is shown as formed from sheet metal, the top portion 1 and the sides 2 being formed from one integral sheet with the ends 4 electrically welded or otherwise secured thereto to provide an air tight compartment. The lower longitudinal edges of 45 the sides 2 are flared outwardly as indicated at 2^a; bent inwardly as indicated at 2^b, and thence upwardly as indicated at 2^c.

The bottom is stamped from a single piece 50 of sheet metal so as to provide a central raised portion 5 and a marginal flange 6 extending completely about the raised portion with its outer edges slightly bent up as indicated at 6^a.

One of my improved latches and guides 55 is located at each corner of the raised portion 5 of the bottom. Each device has a supporting housing consisting of two walls 7 and 8 preferably constructed of a single piece of sheet metal. The lower portions of 60 these walls are arranged at right angles to each other, so as to conform to the shape of the corners of the bottom portion 5, while the upper portions thereof are curved or inclined inwardly toward the center of the 65 vault bottom, as indicated at 7^a and 8^a, and project above the same, so as to provide a pointed inclined guide portion. The housings thus formed are secured to the respective corners 7 of the raised portion 5 in any 70 suitable way, preferably by electrically welding the wall 7 to the side of the raised portion of the bottom and also welding the lower edges of both walls to the flange 6.

Secured to the inner wall of the housing 75 member 8 is a casing 9 open at both ends, the housing member 7 having a slotted opening 10 in line with the opening through the casing. Slidably mounted in this casing 9 is a latch 11 having a bevelled nose 11^a 80 which projects through the slotted opening 10. The latch 11 has an elongated slot 12 into which projects a tongue 13 punched from the wall of the casing 9. A coil spring 14 connected to the inner end of the latch 11 85 and also to the housing member 7 normally projects the latch to locking position.

During transportation the two latches at 90 each end of the bottom are tied together by a wire secured in the slotted openings 12 to hold them out of locking position, these 95 wires being removed before the bottom is lowered into the grave. When the top portion of the vault is lowered, the inturned portions 2^a, riding on the curved guides, will 100 steer the top portion to cause it to properly seat itself upon the flange 6. When the inturned portions 2^b strike the bevelled noses of the latches, the latches are forced back until released by the upturned parts 2^c 105 whereupon they will spring to the locking position shown in Fig. 1 with the lower edges thereof engaging the upper edges of the upturned portions 2^c.

It will be seen that I provide a guide and 110 latch of simple construction which are entirely concealed after the upper portion of the vault has been locked to the bottom.

Having thus described my invention, I claim:

1. In a structure of the character described, the combination, with a vault consisting of 5 a separate bottom and an upper chambered portion, of spring pressed latches carried by said bottom and guides on said bottom to steer the upper portion to position to be engaged by said latches, said latches being housed by said guides, said latches and guides being located within the said chambered portion entirely concealed when the parts are locked together. 10
2. In a structure of the character described, 15 the combination with a vault having a separate bottom with a raised portion and marginal flange to receive the top portion of said vault, of a guide and spring latch located at each corner of said raised portion within the 20 top portion of the vault to guide the top portion and lock it in position on said bottom, said latches being housed by said guides.
3. In a structure of the character described, 25 the combination with a vault having a separate bottom with a raised portion and a marginal flange to receive a top chambered portion, of a support secured at each corner of the raised portion of said bottom, each of said supports having an inclined upper end 30 to form a guide, and a spring latch carried by each support.
4. In a structure of the character described, 35 the combination with a vault having a separate bottom with a raised portion and marginal flange to receive a top chambered portion, said top portion having an inturned lower edge, of a plurality of guides located at the respective corners of said raised portion within the top portion of said vault co-operating with the inturned edges of said top portion to guide the same to position on said bottom, and a series of spring latches to engage said inturned edge to latch the top to position, said latches being housed by said guides. 40 45
5. In a structure of the character described, the combination with a vault having a top chambered portion and a separate bottom, said bottom formed with a raised central portion, of a plurality of angularly-shaped 50 supports secured to the corners of said raised portion having inclined upper ends projecting above the top of said raised portion to form guides, said guides co-operating with the lower edge of said chambered portion to 55 guide the same to position, and spring latches carried by said supports arranged to engage the lower edges of said top portion to lock it in position.
6. In a structure of the character described, 60 the combination with a vault having a top chambered portion, and a separate bottom, the bottom having a raised portion having corners, of a housing secured to each corner, a casing carried by each housing open at 65 both ends, the housing having a slot in line with the opening through said casing, a spring pressed latch in said casing projecting through said slot, a slotted opening in said latch and projection on said casing projecting into said slotted opening. 70

In testimony whereof, I have hereunto set my hand this 1st day of August, 1921.

JACOB R. BURKHARDT.
